(57) **ABSTRACT**

Disclosed is a terrace canopy, comprising a beam which a top side, a bottom side, an inner side and an outer side, and, in its cross-section, is provided with: a screen cavity and a U-shaped space at the bottom side of the beam which is located below the screen cavity and open at its bottom side. The U-shaped space is configured to hold a first profile and a second profile, different from the first profile, and is provided with: a first and a second connection means configured together to hold the first profile or the first connection means and a connection wall portion configured together to hold the second profile. By leaving the U-shaped space open at its bottom side and providing the connection means, it is possible to integrate other profiles into the beam.

TERRACE CANOPY

CROSS-REFERENCE TO RELATED APPLICATION(S)

This present application is a national stage application of International Patent Application No. PCT/IB2021/053275, filed Apr. 21, 2021, which claims priority to Belgium Patent Application No. 2020/5265, filed Apr. 21, 2020, the disclosures of which are hereby incorporated by reference in their entireties.

TECHNICAL FIELD

The present invention relates to a terrace canopy.

STATE OF THE ART

Terrace canopies are usually set up to screen off or clear an outdoor area. For instance, such screen devices are often set up near houses, restaurants, shops, etc. to screen off an outdoor terrace or the like from sunlight, precipitation and/or wind, or conversely, to temporarily allow in sunlight. These terrace canopies can be implemented, for example, in the form of awnings, pergolas, verandas, carports, a pavilion, etc.

Such a terrace canopy typically comprises a roof frame that is at least partially supported by columns. Exceptionally, the roof frame may also be supported by another roof construction. The roof frame is generally constructed of several beams that are composed into one or more frames into which a roof infill can be attached. The beams themselves are often a composition of a plurality of individual profiles. Such a roof frame is typically supported by four (or more) columns between which a wall infill may be provided. Likewise, less columns may be used in case the roof frame is supported by other structures, such as a wall of an already existing structure.

The roof infill may be stationary or movable, for example, a retractable roof. The roof infill of a retractable roof may, for instance, consist of a rollable cloth or screen, slats that rotate around their axis, or of segments that can slide over each other. The segments may be panels that are partly made of (laminated) glass or plastic, such as PC or PMMA. Depending on the choice of material, the light transmission and robustness of the roof may be adjusted to the desired application. The wall infill can also be stationary or movable. Examples are a rollable cloth or screen or movable, i.e. slidable or foldable, panels.

A known problem with such terrace canopies is the amount of customization and/or the number of standard components that may be required to provide sufficient variation in the construction possibilities of the terrace canopy.

BE 2014/0015 discloses a terrace canopy which aims to at least partially solve the aforementioned problem. BE 2014/0015 discloses a beam for a terrace canopy, which beam is provided with an internal cavity for the purpose of draining precipitation incident on the terrace canopy, to a front end of the beam. Above the cavity, a space is provided in which a screen roll can be arranged which can be downwardly unrolled, the screen then being located between the cavity and the outer side (formed by the front cover of the beam).

In practice, it is also possible to use other types of wall infill, in particular sliding panel walls, with the beam disclosed in BE 2014/0015. To this end, the screen cavity is

2

closed at the bottom side and an additional wall profile is attached to the bottom side of the beam.

However, by attaching an additional wall profile, the total size of the beam increases, which is undesirable, among others, for reasons such as possible changes in the headroom, wind load and aesthetic appearance. In addition, a seam can be seen between the beam and the wall profile, which is visually undesirable.

In summary, it has turned out in practice that the beam disclosed in BE 2014/0015 still offers too little the possibility of an integration of the different types of side wall infill that are common with terrace canopies.

IT201800001632 A1 also discloses a terrace canopy comprising a beam intended to hold a sidewall infill. To this end, the bottom side of the beam is provided with several U-shaped chambers for guiding wall parts. The entire bottom side of the beam, including the external gutter, is integrally manufactured. There is therefore no possibility to use different types of side wall infill.

DESCRIPTION OF THE INVENTION

It is an object of the present invention to provide a beam for a terrace canopy that allows more integration of the types of side wall infill common with terrace canopies.

This object is achieved by a terrace canopy comprising a beam, the beam having a top side, a bottom side, an inner side and an outer side, and, in its cross-section, is provided with: a screen cavity configured to hold a screen roll; and a U-shaped space at the bottom side of the beam which is located below the screen cavity and is formed by a top wall, an outer side wall and an inner side wall, said U-shaped space being open at its bottom side, wherein said U-shaped space is configured to hold a first profile and a second profile, different from the first profile, said U-shaped space being provided with: a first connection means and a second connection means configured together to hold the first profile; or said first connection means and a connection wall part configured together to hold the second profile, the connection wall part being configured to be attached against a wall of the second profile.

Although a (limited) space is provided below the gutter in the terrace canopy disclosed in BE 2014/0015, this space is completely closed off by the design of the gutter profile such that the space has no or only limited functionality. Limited functionality here means that the space can be used for receiving one or more bolts for securing an additional wall profile below the beam.

The present invention improves upon this by leaving that same space open at its bottom side and by providing the necessary connection means. This allows other profiles, for example a wall profile, to be introduced into that space. This benefits the variation in functionality.

As already described above, a similar functionality is possible with the beam disclosed in BE 2014/0015 by attaching an additional wall profile to the bottom side of the beam.

The present invention improves on this in that the open space below the internal gutter allows the additional wall profile to be integrated into the beam without showing a visually visible seam on the outer side of the beam.

The use of several connections for attaching the first or the second profile is also advantageous. In general, for the strength and mutual positioning, among other things, two separate connections should be used for each connection of two profiles. The fact is that if only one connection is used for two profiles, there is more clearance in the mutual

positioning, which may give rise to a divergent positioning, in particular due to wind loads and/or precipitation.

In addition, the first two connection means (e.g. hooks, slots, pins, etc.) can be used for the connection of a relatively light profile (e.g. a closure profile), while the first connection means and the connection wall part can be used for connecting a relatively heavy profile (e.g. a wall profile). In addition, in a wall-to-wall attachment (i.e. via the connection wall part) the first connection means already serves for the correct positioning of the second profile relative to the U-shaped space.

In an embodiment of the present invention, the first connection means is provided on the inner side wall or the outer side wall of the U-shaped space, in particular on the outwardly or inwardly facing side thereof, respectively, and more particularly on the bottom end thereof, and is preferably formed by a hook.

In an embodiment of the present invention, the second connection means is provided on the outer side wall or the inner side wall of the U-shaped space, particularly on the inwardly or outwardly facing side thereof, respectively, and more particularly on the top end thereof, and is preferably formed by a hook.

In an embodiment of the present invention, the connection wall portion is provided on the inner side wall or the outer side wall of the U-shaped space. Preferably, the inner side wall or the outer side wall of the U-shaped space has at least two wall parts located in a different plane, the connection wall part being formed by one of said wall parts.

These different embodiments provide a flexible design of the U-shaped space and allow the connections (i.e. both the connection means and the connection wall portion) to be placed at different locations in the U-shaped space. This allows to optimally design the U-shaped space depending on the desired application. The wall parts in a different plane also avoid that the separate connections have a negative influence on each other, for instance obstruct each other, since they may engage on a different wall part.

In an embodiment of the present invention, the first connection means and the second connection means are each on a different one of the inner side wall and the outer side wall of the U-shaped space and/or that the connection wall portion forms part of one of the inner side wall and the outer side wall of the U-shaped space and the first connection means is located on the other of the inner side wall and the outer side wall of the U-shaped space. In this way, both the first profile and the second profile are attached to opposite legs of the U-shaped space, which increases the stability of the connection.

In an embodiment of the present invention, the beam comprises the first profile, the first profile being a closure profile that closes off the U-shaped space. Preferably, the closure profile is provided with a first complementary connection means and a second complementary connection means, wherein the closure profile is connected to the U-shaped space by connecting the first complementary connection means with the first connection means and by connecting the second complementary connection means with the second connection means. If there is no need for a wall infill, the U-shaped open space can be closed off such that the internal structure of the beam is hidden from view.

In an alternative embodiment of the present invention, the beam comprises the second profile, the second profile being a wall profile located in the U-shaped space and configured to guide and/or hold a wall panel. Preferably, the wall profile is provided with a first complementary connection means and with a complementary connection wall part, wherein the

wall profile is connected to the U-shaped space by connecting the first complementary connection means to the first connection means and by connecting the complementary connection wall part to the connection wall part by means of a connection means. Integrating a wall profile allows to provide a wall infill, in particular a movable wall infill, in the terrace canopy.

In an advantageous embodiment of the present invention, the wall profile comprises a rail configured to guide at least one wall part. By integrating the rail into the beam, there is no longer any need for guiding at the bottom side of the wall parts such that they cannot form an obstacle for a smooth passage below the terrace canopy if the wall parts are open.

In an embodiment of the present invention, the inner side wall or outer side wall of the cavity is provided with a third connection means, in particular a hook, especially on the inwardly facing side of the respective inner side wall or outer side wall and more especially at the bottom end thereof. This further increases the possibilities to connect profiles in the U-shaped space such that the functionality of the beam improves.

In an embodiment of the present invention, the beam comprises a gutter portion located at least partially below the screen cavity and configured to drain precipitation incident on the terrace canopy to an end face of the beam, wherein said U-shaped space forms part of the gutter part. Preferably, the gutter part is integrally formed. The gutter part provides the desired water drainage from the terrace canopy. The integral forming of the U-shaped space avoids that there is a visible seam between the gutter part and the U-shaped space.

In an embodiment of the present invention, the beam comprises a base member which, in its cross-section, includes: an upright inner side wall provided at the top with a first upper connection means, in particular a female pin connection element, and at the bottom is connected with the gutter part; and a horizontal wall extending from the upright inner side wall towards the outer side of the beam, the upright inner side wall and the horizontal wall of the base part and the top wall of the inner cavity delimiting said screen cavity.

In the terrace canopy disclosed in BE 2014/0015, the base portion of the beam thereof is provided with a first attachment means adjacent the end of the horizontal wall and a second attachment means near an end of an upright wall extending from the location of the first attachment means, such that there is a certain moderate distance between the attachment means. This means that the space between the two attachment means, after placing a further profile, such as a front cover, cannot contribute to the variation in functionality of the beams.

Hence, it is advantageous to provide, near the end of the horizontal wall, two connection means, in contrast to only one connection means in the beam of BE 2014/0015. In particular, the two connection means allow to connect a plurality of functionally different connection profiles with the end of the horizontal wall without the need to provide a connection on another location of the base portion, as is the case in BE 2014/0015. Hence, there is less loss of space in the base portion.

In an embodiment of the present invention, the base part and the gutter part are formed as separate profiles, wherein the upright inner side wall of the base profile at its bottom is provided with at least one, preferably at least two, connection means and that the gutter profile is provided with at least one, preferably at least two, corresponding connection means for connecting the base profile to the gutter

profile. The use of separate profiles has the advantage that the beam is easier to manufacture. It has been found that an extrusion process for manufacturing one profile in which the base part and the channel part are incorporated, is technically difficult to realize, in particular in view of the considerable height of such a profile.

In an embodiment of the present invention, the gutter portion comprises an inner gutter and the top wall of the U-shaped space is the same as the bottom wall of the inner gutter. In other words, the space is located directly below the inner gutter such that the overall height of the beam is delimited.

In an embodiment of the present invention, the gutter part is provided with: a substantially external gutter which is provided for draining precipitation incident on the terrace canopy, which external gutter is formed by an upright inner side wall, a bottom and an intermediate wall that is substantially in line with the inner side wall; said inner side wall extending downwardly from the bottom; and two connection means, wherein a first of the two connection means is located near the transition between the bottom and the upright inner side wall and in particular comprising a pin connection element, and wherein a second of the two connection means is located at an end of the branch and especially comprises a hook. By providing an external gutter, precipitation, incident on the terrace canopy, can be drained to the cavity. In addition, the two connection means allow to use the space below the external gutter functionally since in this space, a plurality of functionally different profiles can be provided.

In an advantageous embodiment of the present invention, the beam comprises a finishing profile which is connected to the gutter part by means of the two connection means. The finishing profile can be formed by one of: a wall profile, preferably comprising a rail configured to guide at least one wall portion; a closure profile, which is preferably substantially L-shaped; and a lighting holder profile. Integrating a wall profile allows to provide a wall infill, in particular a movable wall infill, in the terrace canopy. By integrating the rail into the beam, there is no longer any need for guiding on the bottom side of the wall parts such that they cannot form an obstacle for a smooth passage below the terrace canopy if the wall parts are open. The closure profile serves to hide the internal structure of the beam from view if no functionality is desired below the external gutter. The lighting holder profile allows to integrate lighting for the terrace canopy into the beam.

In an embodiment of the present invention, the U-shaped space is located directly below the screen cavity. This delimits the total height of the beam. In such an embodiment, a gutter (part) is preferably provided along the U-shaped space, which gutter is configured to drain precipitation incident on the terrace canopy to a front end of the beam.

BRIEF DESCRIPTION OF THE DRAWINGS

The invention will hereinafter further be explained in detail with reference to the following description and to the accompanying drawings.

FIG. 1 shows a schematic view of a terrace canopy according to the invention.

FIGS. 2A to 2J show alternative embodiments of the terrace canopy with different wall infills.

FIGS. 3A to 3K each show a cross-section through an alternative embodiment of an external pivot beam with different wall infill functionality.

FIG. 4 shows a cross-section through a basic embodiment of a tension beam.

FIG. 5 shows a section through an embodiment of a central pivot beam.

FIGS. 6A to 6C show individual profiles used in the construction of the external pivot beam and/or the tension beam.

FIG. 7 shows a schematic representation of an alternative external pivot beam according to the invention.

EMBODIMENTS OF THE INVENTION

The present invention will hereinafter be described using particular embodiments and with reference to certain drawings, but the invention is not limited thereto and is only defined by the claims. The drawings presented here are only schematic representations and are not limiting. In the drawings, the dimensions of certain components may be shown enlarged, which therefore means that the components in question are not shown to scale, and this for illustrative purposes only. The dimensions and relative dimensions do not necessarily correspond to the actual practical embodiments of the invention.

In addition, terms such as "first", "second", "third", and the like are used in the description and in the claims to distinguish between similar elements and not necessarily to indicate a sequential or chronological order. The terms in question are interchangeable under appropriate circumstances, and the embodiments of the invention may operate in other sequences than those described or illustrated herein.

The term "comprising" and derivative terms, as used in the claims, should not be construed as being limited to the means stated thereafter; the term does not exclude other elements or steps. The term should be interpreted as a specification of the mentioned properties, integers, steps, or components referenced, without excluding the presence or addition of one or more additional properties, integers, steps, or components, or groups thereof. The scope of an expression such as "a device comprising the means A and B" is therefore not limited only to devices consisting purely of components A and B. On the other hand, what is intended is that, for the purpose of the present invention, the only relevant components are A and B.

With reference to FIGS. 3, 4 and 6, each reference to an orientation of the beams will be interpreted with reference to the position when mounted in the terrace canopy. In this way there are four orientations, namely above, below, outer side and inner side. Here, "above" refers to the part of the beam that is or will be oriented towards the top surface (the sky, e.g. the open sky), "below" refers to the part of the beam that is or will be oriented towards the ground plane (the soil, e.g. the terrace floor), "outer side" to the part of the beam that is or will be oriented away from the roof, i.e. away from the roof infill (i.e. the left side in FIGS. 3, 4 and 6) and "inner side" to the part of the beam that is or will be oriented towards the inner side of the roof, i.e. towards the roof infill (i.e. the right side in FIGS. 3, 4 and 6).

The term "substantially" includes variations of +/-10% or less, preferably +/-5% or less, more preferably +/-1% or less, and more preferably +/-0.1% or less, of the specified state, insofar as the variations are applicable to function in the disclosed invention. It is to be understood that the term "substantially A" is intended to also include "A".

FIG. 1 illustrates a terrace canopy 1 for a ground surface, for example a terrace or garden. The terrace canopy comprises a plurality of columns 2 that support different beams 3, 4, 5. The columns and beams together form frames to

which wall infills 6 and/or roof coverings 7 can be attached as described hereafter. The terrace canopy 1 comprises three types of beams 3, 4, 5, namely:

- a beam 3 which, on the outside of the terrace canopy 1, serves as an external pivot beam 3;
- a beam 4 which, centrally in the terrace canopy 1, serves as a central pivot beam 4; and
- a beam 5 which serves as a tension beam 5.

It will also be appreciated that the beams 3, 4, 5 may be attached to other structures, for example a wall or facade, instead of resting solely on columns 2 as shown in FIG. 1. In such a way, the terrace canopy 1 can generally be used to shield an outdoor space, as well as an indoor space.

FIGS. 2A to 2J show terrace canopies 1 with alternative wall infills 6. The terrace canopies 1 shown have in common that four support columns 2 are provided which support a frame, also called a roof frame. The frame is formed from two external pivot beams 3 and two tension beams 5 in between a roof covering 7 is provided.

In the embodiments shown, the roof covering 7 is formed by slats which are rotatably attached at their front ends to pivot beams 3. The slats are rotatable between an open position and a closed position. In the open position, there is an intermediate space between the slats through which, for example, air can be introduced into the underlying space or can leave this underlying space. In the closed position, the slats form a closed roof with which the underlying space can be shielded from, for example, wind and/or precipitation, such as rain, hail or snow. For the drainage of precipitation, the slats are typically arranged sloping towards one of both pivot beams 3.

The slats are typically manufactured of a rigid material. This can be aluminium, for example. Aluminium has many advantages as a material, as it is at the same time robust and light-weighted, it can withstand bad weather conditions and requires little maintenance. However, other materials are also suitable and their advantages or disadvantages are assumed to be known by the skilled person. A slat can be produced using various techniques depending on the material, including extrusion, cutting, setting, casting, welding, etc. The appropriate production technique is assumed to be known by the skilled person. Preferably, the slats are manufactured by means of an extrusion process. Optionally, filling elements of, for example, polycarbonate, glass, wood, etc. can be used to fill the hollow slats at least partially, for instance to obtain a different appearance of the slat.

Additionally, in an embodiment, in their open position, the slats may optionally be provided slidably in the terrace canopy 1, in order to further increase the control options in terms of incidence of light, radiant heat and ventilation.

More generally, the roof covering 7 is stationary or movable. A movable roof covering comprises, for example, tiltable and/or slidable slats (such as described above) and/or roll-in/roll-out screens and/or slidable panels. The individual elements of the movable roof covering 7 in their closed position form a substantially watertight roof with which the underlying space can be screened off from, for instance, wind and/or precipitation, such as rain, hail or snow. This roof covering 7 is typically drained to the pivot beams 3, 4 and from there directly or via the tension beams 5 to the columns 2. By sliding and/or rotating the slats and/or the panels and/or by rolling in a screen, the roof covering 7 can be at least partially opened and/or closed in order to be able to determine the incidence of light, radiant heat, ventilation, precipitation, etc. to the space below the roof covering 7 as desired.

Wall infills 6 are typically intended to screen openings below the terrace canopy 1 between the columns 2. The wall infills 6 can be stationary or movable. Movable side walls comprise, for example, roll-in/roll-out screens and/or wall elements that are slidably arranged with respect to each other, etc. Stationary side walls can be manufactured of various materials, such as plastic, glass, metal, textile, wood, etc. Combinations of different wall infills 6 are also possible.

FIG. 2A illustrates a wall infill in the form of a roll-in/roll-out screen 6a. The screen 6a extends between two adjacent columns 2 and can be rolled out from the external pivot beam 3. The screen 6a mainly serves as a wind and/or sun screen.

FIG. 2B illustrates a wall infill in the form of sliding wall panels 6b. In the embodiment shown, three panels 6b are provided on either side of the wall. The panels 6b are slidable in pairs (namely one on either side) in a rail provided for this purpose in the external pivot beam 3. On the ground, also a guide 99 is provided for the wall panels 6b, but this guide 99 is optional. FIG. 2C illustrates the terrace canopy 1 of FIG. 2B with the wall panels 6b in their closed position. The wall panels 6b are transparent and preferably made of glass. Naturally, non-transparent wall panels 6b are also possible. Their function is mainly wind and water protection, but depending on their material, sun protection is also possible. A combination of the wall infills of FIGS. 2A to 2C is shown in FIG. 2D. There, a double wall infill is provided, which, on the one hand, comprises a roll-in/roll-out screen 6a and, on the other hand, slidable wall panels 6b (in this case four panels 6b on either side).

Another type of wall infill is shown in FIGS. 2E and 2F. The wall infill comprises foldable wall panels 6c. The wall panels 6c are foldable towards the column 2. FIG. 2F illustrates the terrace canopy 1 of FIG. 2E with the wall panels 6c in their closed position. Additional wall panels 6c are required to cover the entire wall between the columns 2. The wall panels 6c are transparent and preferably made of glass. Also, non-transparent wall panels 6c are also possible. Their function is mainly wind and water protection, but depending on their material, sun protection is also possible. The same type of wall infill, i.e. foldable wall panels 6c, is also shown in FIG. 2G. However, in this case, the panels 6c are located below the external pivot beam 3, while, in the embodiment of FIGS. 2E and 2F, the panels 6c, in their closed state, almost completely cover the external pivot beam 3.

FIGS. 2H to 2J illustrate stationary wall infills 6d. The characteristic feature of the stationary wall infill 6d is that it is possible to have it continue uninterruptedly on the outer side of a column 2. In other words, the column 2 may be hidden from view as in FIG. 2H. The stationary wall infill 6d can also be completely transparent as in FIG. 2I or partly transparent as in FIG. 2J. The function of a stationary wall infill depends on the type and generally includes wind, water and sun protection.

The different variations of beams 3, 4, 5 will be described with reference to FIGS. 3 to 6. The beams 3, 4, 5 are constructed from one or more profiles, as described hereafter. The profiles are typically manufactured of a rigid material. This can be aluminium, for example. Aluminium has many advantages as a profile material, as it is at the same time robust and light-weighted, it can withstand bad weather conditions and requires little maintenance. However, other materials are also suitable and their advantages or disadvantages are assumed to be known by the skilled person. A profile can be produced using various techniques depending on the material, including extrusion, cutting, setting, casting,

welding, etc., with extrusion being the preferred technique. The appropriate production technique is assumed to be known by the skilled person.

The beams 3, 4, 5 of the terrace canopy 1 are hollow as is apparent from FIGS. 3 to 6. The beams 3, 4, 5 are composed of a plurality of profiles 10, 11, . . . , 24. Hereinafter, the different profiles of the beams and their interconnection are briefly discussed. It goes without saying that several variants are conceivable for both the composition of the beams and the interconnection of the profiles, as well as that the specific design of the profiles may differ. In addition, it is also possible that the functionality of different profiles is combined into the same integrally manufactured profile, for instance it is possible to form the base profile 12 together with the intern or external gutter profile 11, 13 as an integrally formed core profile.

It is generally intended to indicate profiles with the same placement and functionality, but with a divergent design with the same reference numeral by using one or more accent marks, e.g. base profile 12 and 12" in FIGS. 3A and 4. It is generally intended to indicate profiles with the same placement but with a modified form as a result of a modification in functionality of the beam by the same reference numeral by the use of letters, for example finishing profile 14, 14a in FIGS. 3A and 3C.

To form the beams 3, 4, 5, the profiles 10, 11, . . . , 24 are interconnected in a specific way. Generally, use is made of pin connections and/or hook connections. In a pin connection typically an elastic element (not shown) is present in a female element, for example a slot element, into which a male element, for example a pin, engages. Hence, a pin connection generally includes an elastically interlocking male and female element; an additional elastic element may be provided for this purpose, but this is not necessarily the case. The elasticity may also arise from the design of the male and female elements. Hook connections typically involve two elements with such a design that they hook into each other. There is no elastic element and the connection is separated by moving the elements away from each other in the correct direction.

In addition, generally, for each interconnection of two profiles, use is made of two separate connections. This improves the strength of the connection, but mainly contributes to the correct mutual positioning of the profiles. The fact is that if only one connection is used for two profiles, there is more clearance in the mutual positioning, which can give rise to a divergent positioning, in particular due to wind loads and/or precipitation loads.

A first design of an external pivot beam 3 is shown in FIG. 3A. The pivot beam 3 is intended not to be provided with a wall infill 6. The pivot beam 3 comprises an interconnected base profile 12 and a double gutter profile 13. The base profile 12 and the double gutter profile 13 are also shown per se in FIGS. 6A and 6B.

The base profile 12 (see FIG. 6A) comprises an upright wall 100 of which a horizontal wall 101 extends to the outer side of the base profile. The upright wall 100 is provided at the bottom with a first lower connection means 103, in particular a hooking means. The upright wall 100 also has a bottom branch 104 which ends in a second lower connection means 105. The lower connection means 103, 105 serve to attach the base profile 12 with the double gutter profile 13.

The double gutter profile 13 (see FIG. 6B) has a central cavity 27 which is formed at the top side by an upper horizontal wall 200. The wall 200 ends on its inner side in an upright branch 202 which ends in a first upper connection means 203, in particular a hooking means. The horizontal

wall 200 is provided on its top side with an upper branch 201 which serves as the second upper connection means 205. The base profile 12 and the double gutter profile 13 are interconnected by, on the one hand, hooking the hooking means 103, 203 into each other (i.e. hook connection 51) and, on the other hand, to connect the walls 105, 205 directly to each other, for example by riveting them (connection 53). Alternatively, these profiles may be manufactured integrally as one single core profile. The drawback here is that such a profile, in view of the considerable height, is not easy to manufacture by means of an extrusion process.

FIG. 6A further illustrates that the upright wall 100 of the base profile 12 is provided on its top side with a bend 106, through which a first upper connection means 102, in particular a female pin connection means, is provided further to the outer side of the base profile 12. As shown in FIG. 3A, the first upper connection means 102 is used to connect the cover profile 15. The cover profile 15 comprises a horizontal wall 400 which merges at its ends into two upright walls 401, 402 and is therefore substantially U-shaped, which is advantageous for avoiding or at least reducing infiltrating water. The bottom side of the horizontal wall 400 is provided with two connection means 403, 404, in particular pins. The pin 403 is used together with the first upper connection means 102 for connecting the cover profile 15 to the base profile 12. Due to the bend 106, the upright wall 100 of the base profile 12 and the upright wall 401 of the cover profile 15 are in the same plane.

The cover profile 15 serves to close off a technical space 26 in the external pivot beam 3. This technical space 26 may serve to house drive means for tilting the slats of the roof covering 7 and/or cabling for, for example, lighting, etc. In other words, the slats of a roof covering 7 are attached to a wall part 100a (see FIG. 6A) which forms part of the upright wall 100 and extends between the horizontal wall 101 and the bend 106. In particular, the slats are partially positioned through these and fixedly attached to an attachment mechanism (not shown) inside the technical space 26. The presence of this attachment mechanism is also part of the reason why the horizontal wall 101 comprises two wall parts 101a, 101b which are at different heights and are connected by a bend 107. The lower placement of wall part 101a leaves sufficient space for the attachment mechanism, while the higher placement of wall part 101b allows the necessary space for arranging a roll-in/roll-out screen in a screen cavity 25.

The horizontal wall is provided near its end with a plurality of connection means, the functionality of which is described hereafter. The connection means comprise a first connection means 108, in particular a hooking means formed by two hooks, and a second connection means 109, in particular a slot. These connection means serve for the attachment of a front cover 14 for shielding the screen cavity 25. This front cover 14 typically forms the outer side of the external pivot beam 3.

The front cover 14 is attached to the base profile by means of a connection profile 16. The connection profile 16 comprises a hollow chamber formed between four walls 411, 412, 413, 414. The wall 414 forms the top side of the connection profile 16 and is provided with a first connection means 35, in particular a hooking means formed by two hooks, corresponding to the first connection means 108. From the top wall 414, a branch 415, in particular elastically deformable, extends towards the inner side of the external pivot beam 3. The end of branch 415 engages in a notch 110 in the base profile 12. On the bottom wall 412, the connection profile 16 is provided with a second connection means

11

416, in particular a female pin connection means. The second connection means 416 serves for receiving a corresponding second connection means 36, in particular a pin. This second connection means 36 is provided on the inner side of the front cover 14. A further attachment of the front cover 14 to the base profile 12 is formed, in particular by a pivotal movement, by placing the end part 37 of the front cover 14 in a slot 109 in the base profile 12 intended for this purpose.

In itself, the above-described attachment of the front cover 14 to the base profile 12 is sufficient. However, in view of the relatively long distance over which the front cover 14 downwardly extends, it is preferable to use an additional support profile 17 and/or a filler profile 18. The support profile 17 comprises a horizontal wall 420 terminating in a first connection means 421, in particular a female pin connection means. A corresponding connection means 39, in particular a pin, is provided on the inner side of the front cover 14. At the other end of the horizontal wall 420, an upright wall 422 and a branch 423, in particular elastically deformable, are provided. The upright wall 422 serves as an abutment against the internal cavity 27 of the double gutter profile 13, i.e. against the outer upright wall 206. The end of the upright wall 422 engages in a notch 207 in the outer side wall 206 of the cavity 27. Similarly, the end of the branch 423 engages in an opening 208 near the corner of the internal cavity 27.

The filler profile 18 is generally U-shaped with a flat bottom side 430 and upright side walls 431, 432. The upright side wall 432, in particular the end thereof, is intended to be fixedly connected to wall part 209a of an outer upright branch 209 of the double gutter profile 13. In an example, rivets are used for this connection. The remaining upright side wall 431 is free and serves as an abutment for the bottom side of the front cover 14. If desired, the upright side wall 431 can also be fixedly attached to the front cover 14. Finally, it should be noted that the upright side wall 432 is provided with a connection means 433, in particular a pin, the function of which will be described later.

In the embodiments shown, the front cover 14 is further provided with a reinforcing rib 41 and a slot 42. The reinforcing rib 41 contributes to the rigidity of the front cover 14 and is useful for obtaining the required resistance at higher loads, especially when bridging relatively long lengths. The function of the slot 42 is hereafter described with reference to FIG. 3B.

It is clear that the front cover 14 is detachable by disconnecting several of the connections. Thereby, the screen cavity 25 is accessible such that modifications, adjustments and/or repairs may be made, if necessary. In a similar manner, the cover profile 15 is removable for modifications, adjustments and/or repairs of elements in the technical space 26, such as the drive of the slats that may form the roof infill 7.

FIG. 6A further illustrates that the horizontal wall 101 merges into an outer upright wall 111 which is provided on its bottom side with a lower connection means 112, in particular a hooking means, and on its top side is provided with a second upper connection means 113, especially a female pin connection means. As shown in FIG. 3A, the second upper connection means 113 is used to connect the cover profile 15 via pin 404. Also, the outer side of the upright wall 111 is provided with a branch 114 that may serve as connection means and/or container for one or more components that need to be introduced into space 32. An

12

opening 33 is provided between the front cover 14 and the cover profile 15, in particular the outer side wall 402 thereof.

FIG. 6B shows more details about the double gutter profile 13 of the external pivot beam 3, shown in FIG. 3A. The double gutter profile 13 comprises an upper horizontal wall 200, an outer upright wall 206, a lower horizontal wall 210 and an upright intermediate wall 211 which together enclose the cavity 27. Further walls of the double gutter profile 13 are a lower outer branch 209 which is substantially the extension of the outer side wall 206, a horizontal branch 213 which is substantially an extension of the lower horizontal wall 210, a lower inner branch 212 which is substantially the extension of the intermediate wall 211, and an upright inner side wall 214 extending upwardly from the end 10 of the branch 212 and defining a space 28 together with the branch 212 and the intermediate 211. The walls 209, 212, 213 of the double gutter profile 13 also form a number of spaces. For example, there is a space 29 located below the external gutter 28 and next to the branch 212. Furthermore, 15 there is also a space 30 located between the branches 209, 212. The purpose of these spaces 29, 30 is described hereafter with reference to FIGS. 3D to 3G. However, in the external pivot beam 3 of FIG. 3A, these spaces have no function, such that they can be hidden from view by providing a closure profile 19.

The external pivot beam 3 is intended to be placed on the outer side of the terrace canopy 1 and should provide for water drainage of precipitation incident on the terrace canopy. In particular, this precipitation may, for example, be 30 collected by a slatted roof 7 which drains precipitation to this pivot beam 3. The roof infill 7 drains the precipitation to the pivot beam 3 where it is collected in the external gutter 28. Between the external gutter 28 and the cavity 27 the intermediate wall 29 is present which is provided with one or 35 more openings, for example a series of perforations, such that the precipitation from the external gutter 28 is diverted to the cavity 27. That is why the bottom of the external gutter 28 also preferably slopes towards the cavity 27. The cavity 27 serves as an internal gutter for the passage of precipitation from one or more adjoining pivot beams 3 to a column 2 along which this precipitation may leave the terrace canopy 1.

Furthermore, the double gutter profile 13 is further provided with an inner connection means 215, in particular a 45 female pin connection means, of a lower inner connection means 216, in particular a hooking means, which forms the end of the branch 212 of a lower outermost connection means 217, in particular a hooking means, which forms the end of the branch 209, and a connection means 218, in particular a hooking means, just below the inner gutter 27. The function of the lower outer connection means 217 will be described with reference to FIG. 3G, while the function of the connection means 215, 216 and 218 is described hereafter.

55 The closure profile 19 is substantially U-shaped with a lower wall 440 and two upright walls 441, 443. The lower wall 440 is provided on its top side with a connection means 445, in particular a hooking means, provided to cooperate with the lower inner connection means 216 for the attachment of the closure profile 19 to the double gutter profile 13. The upright inner wall 443 is provided on its top side with a connection means 444, in particular a pin, provided to cooperate with the inner connection means 215 for attaching the closure profile 19 to the double gutter profile 13. 60 Furthermore, the upright outer wall 441 is provided on its top side with a connection means 442, in particular a hooking means, provided to cooperate with the connection

13

means 218 for attaching the closure profile 19 to the double gutter profile 13. The lower outer connection means 446 is in turn provided to cooperate with the connection means 433 on the filler profile 18 for their interconnection.

Furthermore, the external pivot beam 3 is further provided with screw channels 115, 116, 117, 208, 219, 220 for screwing a headboard to an end of this beam 3 with the aid of screws or bolts for the purpose of connecting the beam with a column of the terrace canopy 1. Screw channel 115 is provided on the bottom side of the branch 104; screw channel 116 is provided on the bottom side of wall part 101a; screw channel 117 is provided adjacent to the second upper connection means 113 in the technical space 26; the screw channel 208 is provided on the upper outer corner of the internal gutter 27; and the screw channels 219, 220 are provided below the internal gutter 27 on either side thereof. Of course, more or less screw channels are also possible and/or the placement thereof may differ.

It should be understood that other ways are possible with fewer or more connection means to interconnect the different profiles forming the external pivot beam 3. Additional connections, for example by means of glue, bolts, rivets, etc., may also be provided between certain profiles in order to interconnect these substantially permanently. Rivets can be used, for example, to connect walls 105, 205 or walls 209b, 441 or walls 209a, 432.

As already described above, the external pivot beam 3 (FIG. 3A) is intended to not use a wall infill, unlike the external pivot beams of FIG. 3B and onwards. This also immediately means that this external pivot beam 3 is almost completely visible in the terrace canopy 1. It is therefore advantageous that the visible surfaces have a sleek finish. Examples include: the co-planarity of the front cover 14 and the cover wall 402; the co-planarity of the upright wall 100 of the base profile 12 and the cover wall 401; the co-planarity of the filler profile 18 and the closure profile 19; the only sporadic presence of an opening between visible profile surfaces; etc.

FIG. 3B illustrates a second type of external pivot beam, wherein the pivot beam is intended to form a side wall 6. Identical elements will be indicated by the same numeral and are not described.

The pivot beam of FIG. 3B is designed to hold a roll-in/roll-out screen 6a serving as a side wall (see FIG. 2A) and arranged in the screen cavity 25. The main difference with the pivot beam of FIG. 3A is the absence of support profile 17 and filler profile 18. Namely, these would disrupt the normal operation of the screen 6a. The slot 42 is provided for arranging therein a holder (not shown) which serves as an abutment for the screen 6a when it is rolled in. Alternatively, the slot 42 itself may serve as such a screen roller abutment. The wall 43 (which extends inwardly on the inner side of the front cover 14) and the wall 221 (which extends outwardly on the outer side of the inner gutter 27) may also serve as an abutment for the screen 6a.

FIG. 3C illustrates a third type of external pivot beam, wherein the pivot beam is intended to form a sidewall 6. Identical elements will be identified by the same numeral and are not described.

The pivot beam of FIG. 3C is designed to cooperate with a stationary wall (see FIGS. 2H to 2J). The main differences with the pivot beam of FIG. 3A are the design of the front cover 14a and the filler element 18a and the presence of a drip profile 24 as alternative on the connection profile 16.

The drip profile 24 has a substantially horizontal wall 450 which is provided on its top side with first connection means 35, in particular a hooking means formed by two hooks,

14

corresponding to the first connection means 108 in the base profile 12. The drip profile 24 also has a second connection means 453, in particular a hook as the end of an elastically upright wall 454. This second connection means 453 engages a corresponding connection means 118 (see FIG. 6A), in particular a hook on the bottom side of the lower connection means 112, on the base profile 12. The connection means 35, 108, 118, 453 together ensure the attachment of the drip profile 24 to the base profile 12.

On its outwardly facing side, the drip profile 24 is finished with an upright wall 452 extending downwardly from the horizontal wall 450. In particular, this upright wall 452 is located substantially in the same plane as the cover wall 402. A slot 451 is provided at the bottom side of the horizontal wall 450 which has the same function as slot 109 in the base profile 12, namely an attachment for the front cover 14a, in particular the end 37a thereof. There is also the opening 33 present between the outer side wall 402 of the cover profile 15 and the upright wall 452 of the drip profile 24.

The front cover 14a has again a substantially flat outer side, which, in this embodiment, does not lie in the same plane as the cover wall 402, but is located more towards the inner side of the external pivot beam 3. In particular, the distance between the outer side of the front cover 14a and the upright wall 100 of the base profile 12 indicated as d2 in FIG. 3B is smaller than before. This allows to place the stationary wall 6d such that it lies substantially in the same plane as the cover wall 402. In particular, the stationary wall 6d is located between the outer side of the front cover 14a and the upright wall 452 of the drip profile 24 with its top side substantially against the bottom side of the horizontal wall 450. This also immediately explains the additional function of the drip profile 24, in particular the wall 452, namely, to prevent the incidence of precipitation on the top side of the stationary wall 6d, which precipitation may could damage, discoloration, etc. at the stationary wall 6d.

Again, the front cover 14a is provided on its inner side with a reinforcement 41a which, although the modified shape compared to the front cover 14, has the same function. A filler profile 18a is also provided on the bottom side of the external pivot beam 3. Although the design of the filler profile 18a is changed, compared to the filler profile 18 shown in FIG. 3A, the function is unchanged, namely closing off the space between the front cover 14a and the double gutter profile 13. Further details are therefore not included.

It should be understood that, in an embodiment wherein the stationary wall 6d is not transparent, it is not necessary to mount the front cover 14a on the external pivot beam 3. After all, the front cover 14a is not visible in such an embodiment. However, the filler profile 18a must be made slightly wider such that it fits closely with the stationary wall 6d such that, seen from the inner side of the terrace canopy 1, the pivot beam 3 is finished almost without a visible opening between the pivot beam 3 and the stationary wall 6d.

FIG. 3D illustrates a fourth type of external pivot beam, 60 where the pivot beam is intended to form a side wall 6. Identical elements will be identified by the same numeral and are not described. Changes have also been made to the design of the base profile 12', the double gutter profile 13', the front cover 14', the cover profile 15', the connection profile 16' and the support profile 17' without any change to the functionality such that the modified design is not explained in more detail. It should be noted, however, that

15

connection means 108 which is formed by two hooks (see FIG. 6A) in base profile 12 is now formed by one hook 108'a and one abutment 108'b.

The pivot beam of FIG. 3D is designed to cooperate with a movable wall 6b, 6c (see FIGS. 2B, 2C and 2G). The main difference with the pivot beam of FIG. 3A is the presence of a wall profile 21 in space 29 below the external gutter 28. This also changes the design of the closure profile 19a.

In this embodiment, the closure profile 19a only serves to close off space 30 below the internal gutter 27. The closure profile 19a comprises a horizontal wall 440a which merges on its outwardly facing side into an upright wall 441a which, unlike upright wall 441, is located between the filler profile 18 and the lower outer branch 209 of the gutter profile 13'. In particular, the upper end of the upright wall 441a is connected to wall part 209b (see FIG. 6B), for example by means of rivets or the like. Connection means 446 is identical to the pivot beam of FIG. 3A and is not further described. At the inwardly facing end of the horizontal wall 440a, a connection means 445a, in particular a hooking means, is provided to cooperate with the lower inner connection means 216 for attaching the closure profile 19a to the double gutter profile 13'.

As already described, the external pivot beam of FIG. 3D serves for cooperation with a movable wall 6b, 6c. The wall profile 21 is provided with a guide chamber 460 formed by two upright walls 461, 462 connected to a horizontal upper wall 463. The upright walls 461, 462 together form a rail 464 into which one or more rollers (not shown) can be movably mounted. The wall profile 21 is further provided with a lower wall 465 with an opening 469 therein which opens onto guide chamber 460. A portion of the rollers and/or the wall extends through the opening 469. At the outwardly facing end of the lower horizontal wall 465, a connection means 468 is provided, in particular a hooking means, which is provided to cooperate with the lower inner connection means 216 for attaching the wall profile 21 to the double gutter profile 13'. On the inwardly facing side of the lower wall 465, it merges into an upright wall 466 which is provided at the top with a connection means 467 (corresponding to connection means 444 of closure profile 19), in particular a pin, provided to cooperate with the inner connection means 215 for attaching the wall profile 21 to the double gutter profile 13'. To increase the dimensional stability of the wall profile 21, the top wall 463 of the guide chamber 460 extends against the inner side wall 466.

Considering the presence of only one rail 464 in the external pivot beam of FIG. 3D, this means that only two types of movable wall 6b, 6c are possible. In particular, it is possible to provide a side wall with only one movable panel 6b, slideable in the longitudinal direction of the external pivot beam 3. In other words, this forms a side wall 6b as in FIGS. 2B and 2C with only one or two panels instead of the six panels shown there (three on either side of the terrace canopy 1). Alternatively, a foldable side wall 6c is possible, as shown in FIG. 2G.

FIG. 3E illustrates a fifth type of external pivot beam, wherein the pivot beam is intended to form a sidewall 6. Identical elements will be identified by the same numeral and will not be described.

The pivot beam of FIG. 3E is designed to cooperate with a movable wall 6b, 6c (see FIGS. 2B and 2C). The main difference with the pivot beam of FIG. 3A is the presence of a wall profile 21 in space 30 below the internal gutter 27. This has also changed the design of the closure profile 19b.

The closure profile 19b now only serves to close off space 29 below the external gutter 28. The closure profile 19b

16

comprises a horizontal wall 440b which merges on its inwardly facing side into an upright wall 443, which is provided with a pin 444, identical as with the pivot beam of FIG. 3A, such that a further description is unnecessary. The horizontal wall 440b is provided at its outwardly facing end with a connection means 445b, in particular a hooking means, provided to cooperate with the lower inner connection means 216 for attaching the closure profile 19b to the double gutter profile 13.

As already described, the external pivot beam of FIG. 3E serves for cooperation with a movable wall 6b. The wall profile 21a is provided with two guide chambers 460 which are formed in the same way as the guide chamber 460 of wall profile 21 described with reference to FIG. 3D. Hence, there are the inner and outer upright walls 461, 462 which form the rails 464 and are connected to the horizontal wall 463. For reinforcement, a horizontal wall portion 463a is also provided, connecting the horizontal walls 463 of the separate guide chambers 460. The lower wall 465a is correspondingly provided with two openings 469, one for each guide chamber 460.

A connection means 468a is provided at the inwardly facing end of the lower horizontal wall 465a, in particular a hooking means, which is provided to cooperate with the lower inner connection means 216 for attaching the wall profile 21a to the double gutter profile 13. At the outwardly facing end of the lower wall 21a, an upright wall 470 is provided, which is located between the filler profile 18 and the lower outer branch 209 of the gutter profile 13'. In particular, the upper end of the upright wall 470 is connected to wall part 209b (see FIG. 6B), for example by means of rivets or the like. Also provided is a connection means 471 which is similar to connection means 446 as with the pivot beam of FIG. 3A and serves to cooperate with connection means 433 on filler profile 18 for their interconnection.

In view of the presence of two rails 464 in wall profile 21a, it is possible to provide in each rail one or two movable panels 6b which are slideable in the longitudinal direction of the pivot beam 3, for example by using rollers (not shown). The panels 6b in the different rail can pass along each other. In other words, this forms a side wall 6b as in FIGS. 2B and 2C with only two or four panels instead of the six panels shown there (three on either side of the terrace canopy 1). If desired, a combination can also be made of sliding panels 6b in one of the rails 464 and folding panels 6c in the other rail.

FIG. 3F illustrates a sixth type of external pivot beam, wherein the pivot beam is intended to form a sidewall 6. Identical elements will be identified by the same numeral and are not described.

The pivot beam of FIG. 3F is designed to cooperate with a movable wall 6b, 6c (see FIGS. 2B and 2C). The main difference with the pivot beam of FIG. 3E is the presence of a third rail 464 where normally the filler profile 18 is present. The wall profile 21b is provided with three guide chambers 460 which are formed in the same way as the guide chamber 460 of wall profile 21, 21a, described with reference to FIGS. 3D and 3E. The lower wall 465b is therefore correspondingly provided with three openings 469. The connection of the wall profile 21b on its inner side with the double gutter profile 13 is identical as for wall profile 21a and will not be described in more detail. On its outwardly facing side, the connection of the wall profile 21b with the double gutter profile 13 is formed by an upright wall 472 which extends upwardly from the horizontal wall 463 of the most outwardly extending guide chamber 460. This upright wall 472 ends in an upper connection means 473, in particular a hooking means, which cooperates with the wall 221 (which

extends outwardly on the outer side of the inner gutter 27). The lower end of the front cover 14 abuts against the outer end of the horizontal wall 465b of the wall profile 21b.

In view of the presence of three rails 464 in wall profile 21b, it is possible to provide in each rail one or two movable panels 6b which are slidable in the longitudinal direction of the pivot beam 3, for example by using rollers (not shown). The panels 6b in the different rail can pass along each other. In other words, this forms a side wall 6b as in FIGS. 2B and 2C. If desired, a combination can also be made of sliding panels 6b in two of the rails 464 and folding panels 6c in the other rail.

FIG. 3G illustrates a seventh type of external pivot beam, wherein the pivot beam is intended to form a sidewall 6. Identical elements will be identified by the same numeral and are not described.

The pivot beam of FIG. 3G is designed to cooperate with a movable wall 6b (see FIG. 2D). The main difference with the pivot beam of FIG. 3E is the design of the wall profile 21c with respect to the wall profile 21a. The wall profile 21c comprises a horizontal upper wall 463c from which five upright walls 461c extend downwardly to form four guide chambers 460c. At the bottom, the most inwardly facing upright wall 461c is provided with a horizontal branch 465c comprising a connection means 468c, in particular a hooking means, which is provided to cooperate with the lower inner connection means 216 for the attachment of the wall profile 21c to the double gutter profile 13. The attachment to the outer upright wall 461c is formed by fixedly connecting this wall to wall part 209b (see FIG. 6B), for instance by means of rivets or the like. Furthermore, a connection means 471c is also provided which is similar to connection means 446 as with the pivot beam of FIG. 3A and serves to cooperate with connection means 433 on filler profile 18 for their interconnection.

The wall profile 21c is typically intended for slidable wall panels 6b that are thinner, in comparison to the wall profiles 21, 21a and 21b. In particular, the wall profile 21c is intended for glass wall panels in which a maximum of four (or eight) panels 6b can slide along each other, as shown in FIG. 2D. Due to the lower weight of the wall panels 6b (in view of their relatively low thickness) it is possible to use less strong rails 464c, whereby wall profile 21c is compact such that more wall panels 6c can be provided in the transverse direction of the pivot beam 3. This compact wall profile 21c also allows other forms of wall infill, for instance a screen 6a, to be present in order to arrive at the terrace canopy shown in FIG. 2D. In addition, with glass wall panels 6b, rollers are typically provided on the bottom side of the panels on the ground guide 99 such that the guide in the rails 460c can be embodied more compact or even omitted altogether.

FIG. 3H illustrates an eighth type of external pivot beam, wherein the pivot beam is intended to form a sidewall 6. Identical elements will be identified by the same numeral and are not described.

The pivot beam of FIG. 3H is designed to cooperate with a movable wall 6b, 6c (see FIGS. 2E and 2F). The main difference with the pivot beam of FIG. 3A is the presence of a wall profile 20 that is positioned outwardly relative to the front cover 14a', which therefore also has a modified design, in particular the same design as the front cover 14a with a stationary wall infill, described with reference to FIG. 3C, such that a further description is not included here. It should be noted, however, that the front cover 14a' is located at a different distance from the upright wall 100 of the base profile 12 compared to the front cover 14a of the pivot beam

3, shown in FIG. 3C. The design of the cover profile 15a is also changed. In particular, the horizontal wall 400a has a longer length such that the distance between the pins 403, 404 is larger and such that the outer upright wall 402 is at a larger distance from the upright wall 100 of the base profile 12. This longer length allows to integrate the wall profile 20 into the design of the pivot beam 3 without adversely affecting the quality of the finish.

The wall profile 20 includes a guide chamber 480 which is identical to that of wall profiles 21, 21a and 21b. The guide chamber 480 is therefore limited by inner and outer upright walls 481, 482, an upper horizontal wall 483 connecting the upright walls 481, 482, and a lower wall 485 having an opening 496 therein. The upright walls 481, 482 together form a rail 484 into which one or more rollers (not shown) can be movably arranged. A portion of the rollers and/or the wall extends through the opening 496.

The lower wall 485 has, on its inwardly-facing end, a slot 490 for receiving the end 37a of the front cover 14a' for the attachment of the front cover 14a' to the wall profile 20. This slot 490 is, in particular, formed by a downwardly extending branch 499 that departs from the bottom side of the lower wall 485. At the inner end of the lower wall 485, it merges into an upright wall 486 which has a bend 497 near the centre such that a lower portion of wall 486 is located more inwardly relative to an upper portion thereof. The upright wall 486, in particular the lower part thereof, is provided on its inner side with a first inner connection means 487, in particular a hooking means. The first inner connection means 487 serves to cooperate with the lower connection means 112 (see FIG. 6A) for connecting the wall profile 20 to the base profile 12. The bend 497 allows the upper part of the wall 486 to be positioned more outwardly and to abut against the branch 114. At the top of the upright wall 486 it merges into an upper horizontal wall 488. Also, the upper wall 483 of the guide chamber 480 is connected to this upper wall 488 by support member 495. The horizontal wall 488 is on its inner end provided with a second inner connection means 489, in particular a hooking means, which hooks over the second upper connection means 113 for connecting the wall profile 20 to the base profile 12.

The outer wall 481 of the guide chamber 480 also has an upward upright branch 492 which is provided on its top side with an upper connection means 491, in particular, a female pin connection means. As shown in FIG. 3H, the upper connection means 491 is used to connect the cover profile 15a via pin 404. A connection wall 494 is provided between the horizontal wall 488 and the upright branch 492 for the strength and bearing capacity of the wall profile 20. A branch 493 is also provided on the outer side of the upright branch 492. The lower wall 485 is provided on its outwardly facing side with an upright finishing wall 498 which is located in the same plane as the outer side wall 402 of the cover profile 15a. An opening 33a is provided between walls 402, 498.

Considering the presence of only one rail 484 in the external pivot beam of FIG. 3H, this means that only two types of movable wall 6b, 6c are possible. The purpose of this rail 484 is to hold a foldable side wall, as shown in FIGS. 2E and 2F. However, as already described with reference to FIG. 3D, a single rail 484 can also be used to hold one or two sliding side wall panels. It should further be understood that, if desired, the wall profile 20 can also be provided with several mutually parallel chambers for guiding several wall panels.

FIG. 3I illustrates a ninth type of external pivot beam, wherein the pivot beam is intended to form a side wall 6. Identical elements will be identified by the same numeral and are not described.

The pivot beam shown in FIG. 3I has a combined functionality, namely that of the pivot beams shown in FIGS. 3C and 3H. In other words, the external pivot beam 3 has as side wall infill 6 both a portion with a fixed wall 6d and a portion with a movable, in particular a foldable, side wall 6c. For example, a fixed wall 6d is provided on one side of a side of the terrace canopy 1, while a foldable side wall 6c is present on the other side of the same side.

The front cover 14a and the drip profile 24 of the pivot beam of FIG. 3I are identical to those described with reference to FIG. 3C and the cover section 15a is identical to that described for the pivot beam of FIG. 3H. A further description is therefore not included here. In addition, the wall profile 20a is substantially identical to what was described with reference to FIG. 3H. The only difference is the absence of branch 499 which served as attachment for the front cover 14a. Now, this branch 499 is not necessary since the front cover 14a is held by the drip profile 24 and is closer to the upright wall 100 of the base profile 12 such that there is sufficient space for placing a fixed wall 6d.

FIG. 3J illustrates a tenth type of external pivot beam, wherein the pivot beam is intended to form a side wall 6. Identical elements will be identified by the same numeral and are not described.

The pivot beam shown in FIG. 3J has a combined functionality, namely that of the pivot beams shown in FIGS. 3C and 3E. In other words, the external pivot beam 3 has as side wall infill 6 both a portion with a fixed wall 6d and a portion with a movable, in particular a slidable, side wall 6b. For example, one side of a side of the terrace canopy 1 is provided with a fixed wall 6d, while on the other side of the same side there is a slidable side wall 6b, in particular formed by two wall panels.

All relevant profiles for the construction of the pivot beam shown in FIG. 3J have already been described with reference to FIGS. 3C and/or 3E. A further description is therefore not included here.

FIG. 3K illustrates an eleventh type of external pivot beam, wherein the pivot beam serves for holding a lighting. Identical elements will be identified by the same numeral and are not described.

The pivot beam of FIG. 3K is substantially the same as the one shown in FIG. 3D with the difference that the wall profile 21 has been replaced by a lighting holder profile 10. The lighting holder profile 10 comprises two spaces 500, 501 in which lighting (not shown), such as one or more lamps, LED lighting, etc. can be installed. The space 500 can be used to illuminate the space below the terrace canopy 1, while the space 501 allows to illuminate the area below the pivot beam 3. The space 500 is substantially U-shaped and comprises an upright central wall 502, a top wall 503 and a bottom wall 504. The top wall 503 is provided at its end with an upright inner branch 505 having a connection means 506 thereon (corresponding to connection means 444 of closure profile 19), in particular a pin, provided to cooperate with the inner connection means 215 for attaching the lighting holder profile 10 to the double gutter profile 13'. The space 501 is substantially U-shaped and comprises an upright central wall 502, an top wall 507 and an outer side wall 508. The outer side wall 508 is provided at its bottom end with a connection means 509, in particular a hooking means, which is provided to cooperate with the lower inner connection means 216 for attaching the lighting holder profile 10 to the

double gutter profile 13'. In the spaces 500, 501, additional mounting walls 510, 511 are also provided on which, among other things, the lighting can be attached. It is also possible to arrange diffusers and/or other elements in the spaces 500, 501 for optimizing the light quality. Furthermore, it should be understood that also only one of the spaces 500, 501 can be present.

It should also be understood that combinations of profiles that have not yet been shown, are possible to obtain yet other beams. For example, a beam according to one of the FIGS. 3E to 3F with an additional wall profile 20 according to FIG. 3H. This then allows to have several different types of panel wall infills on the same wall of the terrace canopy 1, for example a sliding wall below the beam and a folding wall on the outer side of the beam.

FIG. 7 shows a schematic representation of an alternative design of an external pivot beam 3. Identical elements will be identified by the same numeral and will not be described. The main difference between the external pivot beam of FIG. 7 and the one of FIGS. 3A through 3K is that there is no internal gutter 27 present. As a result, the U-shaped space 30 is located directly below the screen cavity 25. It is to be understood that the U-shaped space 30 in the external pivot beam 3 is substantially identical to the one shown in FIGS. 6B and 6C. The U-shaped space 30 is thus provided with a number of connection means 218, 216, 217; a number of connection wall parts 209a, 209b; and screw channels 219, 220. Their function is identical to that shown in the embodiments in FIGS. 3A through 3K and will not be further described. It is therefore possible to accommodate different profiles 19, 19a, 21a, 21b, 21c in the U-shaped space 30.

The external pivot beam 3, shown in FIG. 7, also comprises a base profile 12, and an external gutter profile 13. In the embodiment shown, the external gutter profile is an integrally formed U-shaped profile with upright side walls 212, 214 and a bottom 213. The upright side wall 212 is attached at the top to the base profile 12 and also forms the inner side wall 212 of the U-shaped space 30. The walls 209, 210 of the U-shaped space 30 are an integral part of the base profile 12. It should be understood that other divisions between profiles are possible.

FIG. 4 illustrates a design of a tension beam 5. The tension beam 5 shown is intended not to be provided with a wall infill 6. The tension beam 5 shown comprises a base profile 12" and a single gutter profile 11 which are interconnected. The single gutter profile 11 is also shown per se in FIG. 6C. It is to be understood that, in embodiments not shown, the tension beam can be suited and intended for receiving and/or holding a wall infill by using the profiles shown in FIGS. 3B, 3C, 3E, 3F, 3G, 3H, 3I and/or 3J.

The tension beam 5 shown is generally the same as the pivot beam shown in FIG. 3A but with a different type of gutter profile, namely a single gutter profile 11 instead of a double gutter profile 13. Although the profiles 12", 14", 16", 18" of the tension beam 5 have a slightly different design, it should be understood that they are interchangeable with the profiles 12, 14, 16, 18, 12', 14', 16', 18' described above. It is also possible to replace one or more of the profiles 12, 14, 16, 18, 12', 14', 16', 18' in the external pivot beams 3 described above with its modified form of the same profile shown in the tension beam 5 of FIG. 4. Some of the modifications are briefly described. Notch 110 is not provided in the base profile 12", but this functionality is taken over by hook 108" which protrudes downwardly with respect to the horizontal wall 101". The branch 415" on connection profile 16" has been modified accordingly. The inner upright wall 432" of filler profile 18" is shorter and is

21

directly connected to the upright outer side wall **441a** of the closure profile **19a** instead of on the gutter profile. The design of the slot **42**" has been changed.

The single gutter profile **11** is shown in more detail in FIG. 6C. In view of the many similarities with the double gutter profile **13**, it was decided to use the same numbering, but with the first digit "2" replaced by the digit "3". In concrete terms, the design at the top and the outer side of the gutter profiles **11, 13** is identical, such that a further description of elements **300** to **312** and **317** to **321** is superfluous.

The modifications of the single gutter profile **11** compared to the double gutter profile **13** are therefore located on the inner side of this profile, where now no external gutter **28** is present. An additional upright wall part **322** is therefore placed, which is parallel to the intermediate wall **311** (which, for the sake of clarity, in the embodiment of a single gutter profile, is not provided with openings). In this way, the upright walls **302, 312, 322** together form the inner upright wall **323** of the single gutter profile **11**. This is also the externally visible wall, seen by someone located below the terrace canopy **1**. Furthermore, the lower inner connection means **316**, particularly a hooking means, is also substantially identical to connection means **216**, with the difference that the hook only extends outwardly such that the finish of wall **323** is uninterrupted.

Although only one embodiment of a tension beam **5** has been shown, it is understood that the only difference between an external pivot beam **3** and a tension beam **5** is the shape of the gutter profile **11, 13**. Hence, the invention also relates to multiple tension beams having the same functionality of the external pivot beams shown in FIGS. 3A to 3C and 3E to 3J where the double gutter profile **13** is replaceable by the single gutter profile **11** of FIG. 6C.

FIG. 5 illustrates a central pivot beam **4**. Since the central pivot beam **4** is centrally located in the terrace canopy **1**, it is not the intention that a side wall can be located below the beam **4**, which changes the design of a whole number of profiles. Of course, it cannot be ruled out that a wall infill may be present below the central pivot beam **4**.

The central pivot beam **4** is constructed from a limited number of profiles, namely a base profile **22**, a gutter profile **23**, a cover profile **15b** and two closure profiles **19b**. The base profile **22** has a symmetrical construction and is connected to the gutter profile **23** by means of connections **58, 59**. Connections **58, 59** have a different design, whereby connection **58** is shown as a hook connection. However, these connections can be identical to each other. At its top side, the base profile **22** is sealed by a cover profile **15b** by means of pin connections **57**. The gutter profile **23** comprises two external gutters **28** and the central gutter **27** which are separated by intermediate walls **56**. For finishing at the bottom side below the external gutters **28**, use is made of two closure profiles **19b** identical to the one described with reference to FIG. 3E. In particular, the attachment uses a connection means **55**, in particular a female pin connection means, below the external gutters **28**, which cooperates with pin **444**, and a lower connection means **54**, in particular a hooking means, forming the end of the branch **53** and cooperating with hook **445b**. Furthermore, the central pivot beam **4** is also provided with screw channels **50** for screwing a headboard onto an end of this beam **4** by means of screws or bolts.

It should be understood that finishing profile **19b** can also be replaced by LED-holder profile **10**, described with reference to FIG. 3K. If necessary, it is also possible to replace the finishing profile **19b** with wall profile **21** described with

22

reference to FIG. 3D. Optionally, the space **30** below the internal gutter **27** may also be used for a wall profile.

While certain aspects of the present invention have been described with respect to specific embodiments, it is understood that these aspects may be implemented in other forms within the scope as defined by the claims.

The invention claimed is:

1. A terrace canopy comprising a beam, the beam having a top side, a bottom side, an inner side and an outer side, and, in its cross-section, is provided with:

a screen cavity configured to hold a screen roll; and a U-shaped space at the bottom side of the beam which is located below the screen cavity and is formed by a top wall, an outer side wall and an inner side wall, the U-shaped space being open at its bottom side, the U-shaped space being provided with:

a first connection means, a second connection means and a connection wall part, wherein the beam comprises a wall profile located in the U-shaped space and configured to guide and/or hold a wall panel, the wall profile being held in the U-shaped space by the first connection means and the connection wall part which is attached against a wall of the wall profile, and

wherein the wall profile can be removed and replaced with a closure profile and vice versa, the closure profile being configured for closing off the U-shaped space and for being held in the U-shaped space by the first connection means and the second connection means.

2. The terrace canopy according to claim 1, wherein the first connection means is provided on the inner side wall or the outer side wall of the U-shaped space, in particular on an outwardly or an inwardly facing side thereof, respectively, and, more particularly, at the bottom end thereof, and is preferably formed by a hook.

3. The terrace canopy according to claim 1, wherein the second connection means is provided on the outer side wall or the inner side wall of the U-shaped space, in particular on the inner side or outer side facing side thereof, respectively, and more especially at the top end thereof, and preferably formed by a hook.

4. The terrace canopy according to claim 1, wherein the connection wall part is provided on the inner side wall or the outer side wall of the U-shaped space.

5. The terrace canopy according to claim 4, wherein the inner side wall or the outer side wall of the U-shaped space has at least two wall parts which are located in a different plane, wherein the connection wall part is formed by one of the wall parts.

6. The terrace canopy according to claim 1, wherein the first connection means and the second connection means are each located on another of the inner side wall and the outer side wall of the U-shaped space and/or that the connection wall part forms part of one of the inner side wall and the outer side wall of the U-shaped space and the first connection means is located on the other of the inner side wall and the outer side wall of the U-shaped space.

7. The terrace canopy according to claim 1, wherein the closure profile is provided with a first complementary connection means and a second complementary connection means, wherein the closure profile is connected to the U-shaped space by connecting the first complementary connection means with the first connection means and by connecting the second complementary connection means with the second connection means.

8. The terrace canopy according to claim 1, wherein the wall profile is provided with a first complementary connection means and of a complementary connection wall portion,

wherein the wall profile is connected to the U-shaped space by connecting the first complementary connection means with the first connection means and by connecting a complementary connection wall part to the connection wall part by means of an attachment means.

9. The terrace canopy according to claim 1, wherein the inner side wall or the outer side wall of the cavity is provided with a third connection means, in particular a hook, in particular on an inwardly facing side of the respective inner side wall or outer side wall and more particularly at the bottom end thereof.

10. The terrace canopy according to claim 1, wherein the U-shaped space is located directly below the screen cavity.

11. The terrace canopy according to claim 1, wherein the beam comprises a gutter part located at least partially below the screen cavity and configured to drain precipitation incident onto the terrace canopy to a front end of the beam.

12. The terrace canopy according to claim 11, wherein the gutter part is provided with:

a substantially external gutter provided for draining precipitation incident on the terrace canopy, which external gutter is formed by an upright inner side wall, a bottom and an intermediate wall that is substantially in line with the inner side wall;

said inner side wall extending downwardly from the bottom; and

two connection means, a first of the two connection means being located near a transition between the bottom and the upright inner side wall and in particular comprising a pin connection element and a second of the two connection means being located at an end of a branch and in particular comprising a hook,

wherein the beam preferably further comprises a finishing profile connected to the gutter part by means of the two connection means, the finishing profile more preferably comprising one of:

a wall profile configured to guide and/or hold a wall panel; a closure profile, which is preferably substantially L-shaped; and

a lighting holder profile.

13. The terrace canopy (1) according to claim 11, wherein the U-shaped space is located substantially below a channel part, wherein, preferably, the U-shaped space is integrally formed with a gutter portion.

14. The terrace canopy according to claim 1, wherein the beam comprises a base part which, in its cross-section, is provided with:

an upright inner side wall which, preferably, is provided at the top with a first upper connection means, in particular a female pin connection element, and is connected at the bottom to a gutter part; and a horizontal wall extending from the upright inner side wall towards the outer side of the beam,

wherein the upright inner side wall and the horizontal wall of the base part and the top wall of an inner cavity delimit said screen cavity.

15. A terrace canopy comprising a beam, the beam having a top side, a bottom side, an inner side and an outer side, and, in its cross-section, is provided with:

a screen cavity configured to hold a screen roll; and a U-shaped space at the bottom side of the beam which is located below the screen cavity and is formed by a top wall, an outer side wall and an inner side wall, the U-shaped space being open at its bottom side,

the U-shaped space being provided with:

a first connection, a second connection, and a connection wall part, wherein the beam comprises a wall profile located in the U-shaped space and configured to guide and/or hold a wall panel, the wall profile being held in the U-shaped space by the first connection and the connection wall part which is attached against a wall of the wall profile, and

wherein the wall profile can be removed and replaced with a closure profile and vice versa, the closure profile being configured for closing off the U-shaped space and for being held in the U-shaped space by the first connection and the second connection.

16. The terrace canopy according to claim 15, wherein the first connection is provided on the inner side wall or the outer side wall of the U-shaped space, in particular on an outwardly or an inwardly facing side thereof, respectively, and, more particularly, at the bottom end thereof, and is preferably formed by a hook.

17. The terrace canopy according to claim 15, wherein the second connection is provided on the outer side wall or the inner side wall of the U-shaped space, in particular on the inner side or outer side facing side thereof, respectively, and more especially at the top end thereof, and preferably formed by a hook.

18. The terrace canopy according to claim 15, wherein the connection wall part is provided on the inner side wall or the outer side wall of the U-shaped space.

19. The terrace canopy according to claim 18, wherein the inner side wall or the outer side wall of the U-shaped space has at least two wall parts which are located in a different plane, wherein the connection wall part is formed by one of the wall parts.

20. The terrace canopy according to claim 15, wherein the first connection and the second connection are each located on another of the inner side wall and the outer side wall of the U-shaped space and/or that the connection wall part forms part of one of the inner side wall and the outer side wall of the U-shaped space and the first connection is located on the other of the inner side wall and the outer side wall of the U-shaped space.
